(57) **CLAIM**

The ornamental design for a sign edge bumper, as shown and described.

DESCRIPTION

FIG. 1 is a perspective view of the first embodiment of a sign edge bumper, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a sectional view taken along lines 8-8 in FIG. 2;

FIG. 9 is a perspective view of the first embodiment of a sign edge bumper shown in an environment of use;

FIG. 10 is a perspective view of the second embodiment of a sign edge bumper;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a sectional view taken along lines of 17-17 in FIG. 11; and,

FIG. 18 is a perspective view of the second embodiment of a sign edge bumper shown in an environment of use.

The broken line portion of the drawings show environment that form no part of the claimed design.

1 Claim, 10 Drawing Sheets
